UNITED STATES PATENT OFFICE.

MORRIS JACOBS, OF MIDDLETOWN, NEW YORK.

LOCK-NUT.

1,277,423.

Specification of Letters Patent. Patented Sept. 3, 1918

Application filed September 26, 1914. Serial No. 863,722.

To all whom it may concern:

Be it known that I, MORRIS JACOBS, a citizen of the United States, and resident of the town of Middletown, county of Orange, and State of New York, have invented certain new and useful Improvements in Lock-Nuts, of which the following is a specification.

Although much has been done by myself and others in this art, the art itself is so important that the greatest possible advancement and each and every new and original feature is desirable.

I have endeavored to cheapen the cost of manufacture and simplify the operation of the device without in any way detracting or subtracting from its efficiency and usefulness.

The construction and mode of operation of this my latest invention in this art will be fully developed and described as the specification progresses.

The following is what I consider the best means of carrying out this invention.

The accompanying drawings form a part of this specification in which:

Figure 1 shows in plan a nut provided with releasing and additional locking means.

Fig. 1^a is a sectional view of a nut showing means for securing the locking member herein.

Fig. 2 is an elevation of the device shown in Fig. 1 and shows the means for securing the outer end of the locking spear.

Fig. 2^a is in side elevation partly in section and shows another view of the outer secured end of the locking spear.

Fig. 3 shows a locking member and a nut provided with a single perforation through which the additional locking or releasing means may operate.

Fig. 4 shows another means for securing the outer end of the locking spear.

Fig. 5 shows a locking member of somewhat different shape and having certain finite advantages.

Fig. 6 is a side elevation of the locking spear shown in Fig. 5.

Fig. 7 shows a duplex locking spear locking the nut and bolt against relative motion either direction.

Fig. 7^a shows in side elevation a nut wherein the releasing means is arranged at an angle.

Fig. 8 shows in elevation a nut into which is inserted the spear operating means.

Fig. 9 shows in plan another locking spear having definite advantages.

Fig. 10 shows another means for securing the locking spear into the nut.

Fig. 11 shows a slightly different means for obtaining a tension in the locking spear.

Fig. 12 shows in elevation partly in section, a means for securing and retaining the tensional locking member.

Fig. 13 shows an additional means for securing the tensional locking spear.

Fig. 14 shows on a large scale, the relative length of the locking spear before and after the torsional twist has been applied.

Fig. 15 shows on a larger scale a nut having a modified recess.

Figs. 16, 17 and 18 show modified means for holding the spear in the nut.

Figs. 19 and 20 show in diagram the approximate alinement of recesses to obtain the desired results.

Similar reference numerals indicate like parts in all the figures where they appear.

At 1, I have shown a nut and in the Figs. 80 1 to 4 inclusive I will indicate as 1, a common ordinary nut produced by any well known means. At 2 the bolt is shown and this is an ordinary bolt of any length and adapted to fit the nut in the ordinary manner. At the inner face of the nut 1, I produce a recess 3, which may be of any desirable outline but it must connect with the bore in the nut into which the bolt enters, and it must be of sufficient size to allow my 85 spear thrust locking member to operate unrestrained except to the extent that I have found necessary and desirable and will fully describe.

Parallel with the central screw-threaded 95 perforation but spaced certain distances therefrom, I produce a plurality of perforations 4, 5, and 6, and into the perforation 6, I pass a member that has been produced of hard drawn steel wire or of any other 100 similar substance. Before inserting this wire member I cause a right angle bend to be produced therein which will form the locking spear 7, and I may sharpen or reduce the outermost end of this locking spear 105 as shown at 8. The recess 3, is of a depth about equal to one screw-thread, and the wire member is of a diameter that will not allow

the body of the spear 7 to project upward above the face of the nut 1. The spear 7 must, however, be of sufficient length to allow the end 8 to project to a certain extent 5 into the bolt receiving perforation of the nut.

When the wire member has been placed in position, the end that projects beyond the outer face 10, of the nut 1, is secured in a 10 vise and the nut rotated to cause the spear 7 to be firmly impinged upon the wall 11 of the recess 3 and the outer end of the wire member is firmly secured to the nut. The 15 rotating of the wire or nut produces a torsional twist of the wire in the nut for a purpose that shall appear later.

The perforation 4 enters the recess 3 at one side thereof and partly cuts away the 20 wall 11 of the recess. It is through this perforation that I insert a nail 12 or any similar or convenient instrument to move the spear 7 or the point 8 thereof out of engagement with the bolt 2, thus releasing the point from the bolt and allowing the 25 bolt to be unscrewed from the nut, or the nut removed from the bolt.

It will be observed and understood that the construction thus far described will produce a device that will efficiently hold a nut 30 in which it is contained, against accidental or intentional removal from a bolt until the nail 12 has been inserted to displace the locking spear in the manner shown in Fig. 1. It may, however, be desirable under some 35 conditions to lock the nut against rotation in either direction. As before described the locking spear 7 will hold the nut against removal and to secure it against a further advancement upon the bolt I place a nail 40 12 or any similar article or instrument into the perforation 5, thus holding the spear point firmly into the bolt and preventing a further advance of the nut upon the bolt. The pressure of this nail upon the spear 45 need not be great as I have found that by using a hard steel wire member for the spear, especially a wire member having resiliency or spring that a slight pressure between the device passing through the perforation 5 and the spear will cause the point 8 to bite the bolt with sufficient firmness to forbid the turning of the nut or bolt.

I desire that the spear member, or wire member, as I have sometimes termed it, 55 should be wholly contained within the nut and to accomplish this I produce a saw-kerf 13 at a convenient point in the outer face 10 of the nut 1, and after the end of the wire member or the nut has been rotated to produce the desired tension I bend the end 9 of the spear or locking member downward 60 forcing it into the saw-kerf 13. The end may then be trimmed so that it will assume the contour of the adjacent surface of the 65 nut as shown at 14.

Thus far I have confined my description almost entirely to the construction shown in the first three figures. The general construction and the principles as shown in Figs. 3 and 4 are the same as those already 70 described, but here I have shown a recess of simpler construction it being produced by the use of end mills or similar tools of different diameters thus considerably cheapening the cost of construction, and the finished 75 recess is shown at 15. In this construction I have shown but two perforations parallel with the screw-threaded central perforation and extending quite through the nut.

The smaller perforation 16 receives the 80 wire member the spear end of which passes transversely over the larger perforation 17 and into the bolt hole. To release the spear, a nail or similar instrument is inserted into the perforation 17 and upon the side of the 85 locking spear indicated at R. But to secure the nut against further advancement upon the bolt the nail is withdrawn from its former position and is inserted into the perforation 17 and upon the side of the locking 90 spear indicated at S.

In Fig. 4, I have shown another means of securing the outer end of the wire member into a saw-kerf produced in the outer face of the nut. After the end of the wire member has been turned into the saw-kerf, the metal of the nut is upset or forced into the saw-kerf and upon the wire member as shown at 18. The drawings indicate that a nut of any ordinary shape or size or even 100 a special nut may be utilized with any of my devices.

In Figs. 5 and 6, I have shown a tensional locking spear of somewhat different outline and in the nut shown in Fig. 5 I have 105 produced a recess shaped to receive this particular locking spear. The locking spear consists of the spear end 21 projecting into the screw-threaded perforation of the nut. The spring or tensional member is bent into 110 a partial loop as shown at 22 and into a smaller nearly complete loop as shown at 23. The inner end 24 is flattened as shown at 25 and is forced downward into a shallow perforation. The forcing of the flattened portion 25 into a shallow perforation 115 may be depended upon for securing the whole tensional locking member or I may force the wall of one of the sides of the nut inward upon the projection 25 as shown at 120 26 in Fig. 10 displacing the end or projection 25 by forcing it out of alignment. Another means for securing the tensional locking member 22 may be utilized, and this means is the caving of one of the walls of 125 the recess as shown at 27.

In this Fig. 5, I have shown a releasing perforation 28 and a second perforation 29 which may assist in reinforcing the locking engagement by forcing the spear 21 farther 130

into the screw-threaded aperture. The construction of the securing member as shown has an additional function that of compensating for wear and although this compensation is present to a certain extent in all of my devices here, it is enlarged upon in the following manner:

Before being inserted into the recess, the resilient member being of a length greater than the interior of the recess therefor, the locking member must be forcibly inserted into the recess. When wear occurs the locking member confined by the walls of the recess will advance longitudinally projecting its tongue at all times to a certain desirable extent into the screw-threaded perforation.

At Fig. 7, I show a means for preventing rotation of the nut or bolt in either direction. This means comprises two locking spears 30 and 31 arranged at an angle to each other and to the bolt. Each of these spears is operable in the manner fully described in relation to the other locks and each is releasable through a perforation 32 and 33 respectively. I have provided additional perforations 34 and 35 for reinforcing the locks and perforations 36 and 37 for securing their respective ends of the spear against the possibility of releasing the bolt. I have shown a nail or similar instrument in each of the perforations 36 and 37 but because of the nature of this particular securing means these perforations 36 and 37 may be omitted. The wire member 38 is in this instance a bow, both ends of which are inwardly projecting and I secure this wire member by means of the impressed or upset wall 39 of the nut.

In Fig. 8, I have shown two ordinary nails used for releasing or further securing the securing means and as it may sometimes be desirable to allow a nail to remain in position for an indefinite period I may countersink the outer face of the nut as indicated at 40 allowing the head of a short nail to pass into the countersink and to be concealed under the outer face of the nut. I may also provide a channel 41 for the insertion of another tool for removing the nail.

In Fig. 9, I have shown a construction as important as any other and yet somewhat different in operation. Here the recess proper is composed of a plurality of recesses 43 and 44 which produce the projections 45 and 46 opposite each other and a further projection 47 at the edge of the screw-threaded perforation. The locking member here employed is of somewhat different shape than those thus far shown and described and it is forcibly held between the projections 45 and 46 and caused to firmly impinge upon the projection 47. The outer end of this locking member is turned approximately at right angles as shown at 48 and passes through a groove or channel 49 to the outer side wall

of the nut. Here a saw-kerf may be produced into which the end 48 of the locking member may be forced, after which the wall of the saw-kerf may be upset in the same manner as shown in Fig. 4.

I desire it understood that in all of the developments of my invention the locking spear is, under all conditions a tension member and that even when the bolt is not in place, the locking spear is forcibly engaged against the wall of the recess. Although the bolt will remove the spear from the wall of the recess the removal of the bolt and the releasing nail or instrument will allow the locking spear to return into firm engagement with the wall of the recess.

In Fig. 11, I show a construction somewhat similar to Fig. 9, though in this instance, I have provided two recesses and a single perforation for operating the locking spear. The use of this single perforation 50 is fully described in connection with the perforation 17 in Fig. 3, and in this Fig. 11, the same reference letters are used to indicate the different sides of the locking spear. In the smaller recess 51, I produce an additional perforation which may or may not extend quite through the nut and into this additional perforation, I pass the end of the torsional member. The larger recess 53, provides freedom for the motion of the locking spear and the positive tension desirable in the spear is obtained by confining the shaft thereof between the shoulders 54 and 55 and causing it to strongly impinge upon the shoulder 56.

In Fig. 12, I show one of the means that I have utilized for securing the torsional member. The stem is here shown as passing through a perforation 57 that extends almost wholly through the nut and which is intersected by a saw-kerf 58 into which the outer end 59 of the torsional member is forced. In connection with this and all other of my devices wherein the torsional member extends through the nut, the tension is obtained by passing the torsional member quite through the nut grasping the end thereof in a vise or suitable tool and then turning the nut one full revolution before the end 59 is depressed into the saw-kerf. This will have a tendency to shorten the torsional member as shown in Fig. 14, and a movement of this member even to a small extent in the direction to untwist or relieve the torsional strain, will tend to lengthen the member allowing it to compensate for wear of the spear end.

In Fig. 13, I show another means for securing the torsional member. Here the perforation 60 extends but part way through the nut, and when the end 61 is dropped into this perforation, a suitable tool is caused to force inward the side of the nut as shown at 62 forcing the metal thereof firmly against the stem of the torsional mem-

ber and forcing the torsional member to a greater or less extent out of alignment.

In Fig. 15 I have shown on a large scale a nut provided with two recesses 70 and 71 which together form the desired recess and in each of the recesses I produce a perforation as shown at 72 and 73. Into the perforation 73 I insert the end of a locking spear and I secure it therein by forcing inward 10 the wall of the nut at 74. The outer end of the locking spear passes over the perforation 72 and enters the bolt hole 75 to a limited extent. A nail or other tool may be inserted into the perforation 72 for locking 15 the locking spear.

It will be observed that the arrangement and location of the recesses 70 and 71 produce the abutment or projections 76 and 77 and that the location of the perforation 73 20 is behind the abutment 76 thus when the spear member is placed in position it will be forcibly held under tension occasioned by the perforation 73 the abutment 76 and the abutment 77. When the bolt carries the 25 end of the spear away from the abutment 77 the tension on the spear will be increased as the body thereof will be caused to bear more firmly upon the abutment 76, when however the bolt and releasing means are 30 withdrawn the spear will return to bear firmly upon the abutment 77 as shown.

In Fig. 16 the inner end of the spear member is provided with a return bend 80 which is received into a shallow perforation 81 in 35 the bolt. A center punch may then be used to force a small portion of the wall of the nut inward between the two parts of the return bend as shown at 82.

In Fig. 17 I show in elevation a spear 40 formed as described in connection with Fig. 15 and retained by crimping or forcing inward the wall of the nut.

In Fig. 18 I show another way of securing the end of the spear. This consists of 45 bending the end at right angles continuing it through the counterbore 71 and then bending it once more at right angles and projecting the end through a saw kerf in the wall of the counterbore. The end may be 50 upset outside of the nut as indicated at 84 or I may spot-weld the end of the nut. Spot-welding which consists of producing a local weld by means of an electric needle may be employed to hold the secured end of 55 any of the devices shown. The arrow heads 85 and 86 in this Fig. 18 are intended to emphasize the arrangements of the abutments that combine to forcibly hold the operative end of the locking spear.

60 And now as a general summing up of this invention, I desire to call attention to certain features, so that their importance may be fully appreciated. The locking member 65 is at all times a tensional locking spear thrust member, the spear end of which bites

into the bolt. The spear engaging the bolt, the back or shoulder thereof is forced against the adjacent wall of the recess and instead of the spear accepting all of the strain of the locking, the nut itself takes a 70 greater portion of the strain allowing me to use a spear of lighter construction than would otherwise be required and obtaining for me a strong locking.

The nut itself may be made a commercial 75 product with the different holes and counter-bores produced therein as described. The tension springs may be supplied as separate members to be inserted into the nut by the purchaser and at any subsequent period. No mechanical knowledge is necessary in placing the tensional members or in assembling the lock into the nut and when assembled even by one not familiar with mechanical devices it will be found that the 80 complete device will contain all of the features present were the device assembled by an expert mechanic. The same permanent and tensional locking features will be present and the same compensating in length 85 for wear and the same reinforcing of the locking member by the wall of the nut.

It is obvious that certain parts of one device here shown may be used with another or that certain parts of any may be omitted 90 with the loss of its function. I have described a device so simple in its construction that it may be produced at an extremely low cost; a cost that I have estimated to be about one fourth of a cent. I may further cheapen the construction by providing the die which is used for blanking out the nuts with a plurality of projections so shaped that they will produce in the inner 95 face of the nut the necessary recesses, shoulders and abutments at the time that the nut is blanked out.

Another improvement is that shown in Fig. 7^a wherein the perforation for the insertion of the releasing nail is arranged at 100 an angle so that when the nail is inserted it will hold the wire spear member in a releasable condition without requiring that the point of the nail shall project above the surface of the nut. Its angle may be that 105 shown by the dotted lines α . While I do not claim a perforation or a plurality of recesses as invention I do believe that the location of abutments and shoulders in such a manner that they will create and retain a tension upon a spear member as and in the manner set forth is an invention of the 110 highest order.

115 And as the construction that I have herein shown and described performs few and important functions and as a nut containing abutments for the purpose herein shown is new I therefore believe the nut alone one of the most important features of my invention. The new and special lock held by 120

these abutments is so held that the operation of the bolt can not carry the lock to a position beyond which it is practicable for all purposes.

5 Having carefully and fully described my invention what I claim and desire to secure by Letters Patent is:

1. A device of the character described comprising a nut provided with a recess 10 having walls confining certain sides of said recess and a torsional locking spear secured within said recess and normally forcibly impinging upon certain of the walls thereof for the purpose set forth.

15 2. A device of the character described comprising a nut having a recess upon its inner face and a plurality of perforations communicating with said recess, a resilient locking member contained in said recess 20 and means for operating said resilient member through one said perforation for the purpose set forth.

25 3. A device of the character described comprising a nut having a plurality of connecting recesses upon its inner face and a plurality of perforations one of which intercepts the wall of one said recess, a resilient member within said recesses and projecting into bolt hole and having a stem 30 passing through one said perforation and means adapted to be inserted into another perforation for further securing said locking means.

35 4. A device of the character described comprising a nut having a plurality of recesses and a plurality of additional perforations, a locking spear adapted to pass into one said perforation and a device adapted to pass into another perforation and upon 40 either side of said locking spear for the purpose set forth.

5. A device of the character described comprising a nut having recesses upon its inner face, a torsional spear member within

said recesses and means for insuring or producing a permanent tension to said torsional member as herein specified and for the purpose set forth. 45

6. A device of the character described comprising a nut having a plurality of recesses in the inner face thereof, and a perforation in one of said recesses and out of the axial center thereof, and a torsional member arranged within said recesses and provided with a projection entering said 55 perforation for retaining said torsional member from rotation as herein specified and for the purpose set forth.

7. A device of the character described comprising a nut provided with a plurality 60 of perforations, recesses breaking away the walls of certain of said perforations, and a member arranged in said recesses and forcibly engaged by the walls of said recesses for the purpose set forth. 65

8. A device of the character described comprising a nut having a recess, a plurality of abutments formed in the walls and projecting into said recess and a resilient member retained between said projections entering into the bolt hole of said nut for the purpose set forth. 70

9. A device of the character described comprising a nut having a plurality of adjoining recesses, abutments formed in the 75 walls of said recesses and a resilient member arranged between said projections and adapted to be tensioned by its confinement between said projections as herein specified and for the purpose set forth.

Signed at N. Y. city in the county of New York and State of New York this 24 day of Sept., 1914.

MORRIS JACOBS.
